UNITED STATES PATENT OFFICE.

LOUIS D. VOGEL, OF OMAHA, NEBRASKA, ASSIGNOR TO WOODEN PACKAGE MANUFACTURING COMPANY, OF OMAHA, NEBRASKA.

TRUSSING-MACHINE.

SPECIFICATION forming part of Letters Patent No. 699,121, dated April 29, 1902.

Application filed October 28, 1901. Serial No. 80,305. (No model.)

To all whom it may concern:

Be it known that I, LOUIS D. VOGEL, a citizen of the United States, residing at Omaha, in the county of Douglas and State of Nebraska, have invented a new and useful Trussing-Machine, of which the following is a specification.

My invention is an improved trussing-machine for use in the manufacture of tubs and other similar articles; and it consists in the peculiar construction and combination of devices hereinafter fully set forth and claimed.

In the accompanying drawings, Figure 1 is a side elevation of a trussing-machine embodying my improvements. Fig. 2 is partly a front elevation of the same and partly a vertical sectional view taken on a plane at right angles to that of Fig. 1. Fig. 3 is a top plan view of the same, partly in section on a plane below the plunger and above the forms on the form-carrier. Fig. 4 is a vertical longitudinal central sectional view of the same, taken on a plane at right angles to that of Fig. 2. Figs. 5 and 6 are detail sectional views of one of the expandable plungers.

On opposite sides of a base 1 are a pair of vertical brackets 2, which support a plate 3, that bears on their upper sides. Braces 4 are secured to the inner sides of the said brackets and to the upper side of the base 1. The said brackets are provided with bearings for a shaft 6 and for a power-shaft 7, which is disposed to one side of the shaft 6. The latter has spur-wheels 8 secured on its ends, and the power-shaft has pinions 9, which engage said spur-wheels.

A circular revoluble table 12, which carries a plurality of trussing-forms 13, is mounted on the upper end of a shaft 14, which revolves in bearings 15 in the base 1 and in the plate 3. The trussing-forms are disposed equidistant apart, and the table 12 is provided in its periphery with stop-notches 16, which correspond in number with the trussing-forms and are disposed in line radially with the centers thereof. A stop 17 is provided to engage the stop-notches successively to arrest the rotation of the table and lock the same in position, and the said stop is provided with a suitable pedal 18. As here shown, the upper portion of the stop projects through and oper-

ates in a slotted opening 19, with which the plate 3 is provided on its rear side. It will be observed by reference to Figs. 1 and 3 of the drawings that the revoluble table 12 extends beyond the front side of the plate 3.

Two pairs of vertically-disposed parallel guide-rods 20 have their lower portions disposed and secured in openings in the sides of the base 1 and plate 3. The said guide-rods 20 extend upwardly above the table 12 a suitable distance, and their upper ends are connected together by a cross plate or beam 21. The same is secured to the upper end of the guide-rod by nuts 22 and is provided at its center with a vertical bearing 23, above which is an oil-cup 24. Slide-yokes 25 operate vertically on the respective pairs of guide-rods 20, and a cross-head 26 is operated by the said slide-yokes. The latter are provided on their outer sides with trunnions 27. The gear-wheels 8 have crank-pins 28, which are radially adjustable therein, and pitmen 29 connect the said trunnions of the slide-yokes to the said crank-pins of the gear-wheels 8. In the form of my invention here shown each pitman is composed of a pair of heads 30, which are respectively clamped on and form bearings for one of the trunnions 27 and one of the crank-pins 28, and rods 31, which connect the said heads together. The sections of the respective heads of the pitmen are clamped together by nuts 32, which are screwed on the said nuts 31.

It will be understood from the foregoing that when the shaft 6 is in rotation reciprocating vertical movement will be imparted to the cross-head 26. The ends of the latter engage notches 33 in the inner sides of the slide-yokes. The said notches are of greater vertical extent than the thickness of the ends of the said cross-head, and thereby lost motion is provided between the cross-head and the slide-yokes, the latter at each limit of their stroke moving a slight distance independently of the cross-head while the crank-pins 28 are passing the dead-centers of the wheels 8.

A vertically-disposed plunger-rod 34 operates in the bearing 23 of the cross-plate 21 and passes through a central opening in the cross-head 26. The said plunger-rod has a collar 35 at a suitable distance from its lower

end, which collar is adapted to be engaged by the upper side of the cross-head on the up-strokes of the latter, so that said plunger-rod will be raised by the said cross-head when the latter is moving upwardly. A cap-plate 36 is secured under the central portion of the cross-head by bolts 37. Cushions 38, which may be made of rubber or other suitable material, are interposed between the cross-head 10 and the cap-plate, so that the latter is yieldably connected to the former, and the said cap-plate is provided on its lower side with an annular flange 39 of suitable diameter, the inner side of which is inclined upwardly 15 inwardly, as at 40. The diameter of the cap-plate within its flange 39 corresponds with the exterior diameter of the upper edge of the tubs or other articles to be trussed by the machine. On the lower portion of the plunger-rod are a pair of plunger-heads 41 42, the latter being lowermost and of less diameter than the former. The said plunger-heads are a suitable distance apart and are free to play vertically on the plunger-rod. The latter 20 has a stop-collar 43 to limit the downward play of the plunger-head 41 and a stop-collar 44 to limit the downward movement of the plunger-head 42. It will be understood that the plunger-heads will be of suitable size 25 to enable them to enter a tub or other article in one of the forms 13 on the downstroke of the cross-head.

Prior to setting the machine in motion to cause the cross-head to descend the table 12 will be locked in position to dispose a tub or other article in one of the forms 13 in position directly under the plunger-rod and the plunger-heads carried thereby. On the down-stroke of the cross-head the plunger-heads 30 enter the said tub or other article, expand the staves thereof within the hoops or rings of the tub, and move the staves downwardly to tighten the hoops or rings thereon. As the plunger-heads descend initially in the tub 35 their descent is arrested by their engagement with the inner sides of the staves thereof, and the cross-head continuing to descend the flange 39 of the cap-plate 36 rides over the upper ends of the staves, the beveled inner 40 side of said flange drawing the upper ends of said staves inwardly, evening the same and preventing the staves from splitting. Said cap-plate as it completes its descent with the cross-head levels the upper ends of the staves, 45 as will be understood. Owing to the lost motion which is provided between the cross-head and the slide-yokes the cap-plate is caused to "dwell" on the upper side of the tub for an instant prior to the ensuing ascent 50 of the cross-head.

I provide a vertically-movable arm 45 to release the plunger-heads and raise them in the trussed tub prior to the ascent of the cross-head. This plunger-arm is operated by an 55 eccentric 46, which is fast on the shaft 6.

The plunger-heads are expansible radially,

being provided with radially-movable members 47, which are pressed outwardly by springs 48. This construction of the plunger-heads enables them to be raised and released from the trussed tub by the upward movement of the arm 45.

The revoluble table 12 has a gear 49 on its lower side, which is engaged by a pinion 50 on a shaft 51. A sprocket-wheel 52 on said shaft 51 is connected by an endless sprocket-chain 53 to a sprocket-wheel 54 on a shaft 55, that is also provided with a sprocket-wheel 56. Said wheel 56 is connected by an endless sprocket-chain 57 to a sprocket-wheel 58, 80 which is loose on the shaft 7 and has a clutch member 59. A power-pulley 60, driven by a suitable belt from a counter-shaft, is loose and capable of longitudinal motion on the shaft 7 and provided with a clutch member 59^a to engage said clutch member 59, and thereby impart rotary motion to the wheel 58, and hence to the table 12. Said sleeve has at its opposite side a clutch member 61^a, adapted, in co-action with a clutch member 61 on said shaft 90 7, to impart rotary motion to the latter, and hence to the shaft 6, when said sleeve is unclutched from the said sprocket-wheel 58. Hence rotary motion may be alternately imparted to the table and to the shaft 6, the latter, as before described, operating the plunger-heads when the table is at rest. An arm 62, which is connected to said sleeve and to the arm 18, automatically shifts the power-pulley into engagement with the wheel 58 to 100 rotate the table 12 when the stop 17 is disengaged from the latter and reversely shifts said power-pulley into engagement with the shaft 7 when said stop is in locking engagement with the said table.

Having thus described my invention, I claim—

1. In a trussing-machine, the combination with a relatively fixed form and hoop-support, of a reciprocating element movable to and from the form, a plunger to enter the form and radially expand the staves of the work, said plunger being movable with and independently of the reciprocating element, and means to release the plunger from the interior of the work, prior to the recessional movement of the reciprocating element, substantially as described.

2. In a trussing-machine, the combination with a relatively fixed form and hoop-support, of a reciprocating element movable to and from the form, and having means to engage the upper ends of the staves of the work and limit the outward radial movement thereof, a plunger, carried by the said element, to enter the work and radially expand the staves thereof, and means to release the plunger from the interior of the work prior to the recessional movement of said reciprocating element, substantially as described.

3. In a trussing-machine, the combination with a relatively fixed form and hoop-support,

of a reciprocating element movable toward and from the form, a cap-plate, carried by said reciprocating element, to engage the upper ends of the staves of the work, and having an annular flange to fit around the upper edge of the work and limit the radially-expansive movement of the staves, and a plunger carried by the said reciprocating element and movable independently thereof, to enter the work and radially expand the staves, substantially as described.

4. In a trussing-machine, the combination of a plunger and a form and hoop-support, the one movable toward and from the other, means to cause the plunger to enter and engage the interior of the work in the form and hoop-support, coöperating means to engage and even the outer ends of the staves, and means to release the plunger from the interior of the work prior to the disengagement of the stave-evening means, substantially as described.

5. In a trussing-machine, the combination of a relatively fixed form and hoop-support, a reciprocating element movable toward and from the form, a yieldably-mounted cap-plate, carried by the form, to engage and even the upper ends of the staves and having an annular flange, to limit the expansive radial movement of the staves, and a plunger carried by said reciprocating element, and movable independently thereof, to enter the work, and radially expand the staves, substantially as described.

6. In a trussing-machine, the combination of a form-carrier, a revolute element, slide-yokes connected thereto and reciprocated thereby, guides for said slide-yokes, a cross-head engaged and operated toward and from the form by said slide-yokes, lost motion being provided between said slide-yokes and said cross-head, and a plunger carried by and

movable independently of said cross-head, substantially as described.

7. In a trussing-machine, the combination of a radially-expansible plunger, and a form and hoop-support, the one movable toward and from the other, coöperating means to engage and even the outer ends of the staves, and means to release the plunger from the interior of the work prior to the disengagement of the stave-evening means, therefrom, substantially as described.

8. In a trussing-machine, the combination of a form-carrier, a reciprocating element movable toward and from the form, a plunger operated by said reciprocating element, means to operate said form-carrier to bring a form carried thereby into and out of the path of the plunger, means to operate said reciprocating element, a power element, and means to alternately engage the same with said operating means, substantially as described.

9. In a trussing-machine, the combination of a revolute form-carrier, a reciprocating element movable toward and from a form on said carrier, means to rotate said form-carrier to bring a form carried thereby into and out of the path of the plunger, means to operate said reciprocating element, a power element and means to lock said form-carrier against rotation, said power element being automatically alternately engaged with said form-carrier and reciprocating-element-operating means, by said means for locking said form-carrier, substantially as described.

In testimony that I claim the foregoing as my own I have hereto affixed my signature in the presence of two witnesses.

LOUIS D. VOGEL.
